(57) **CLAIM**

The ornamental design for an electric vehicle, as shown and described.

DESCRIPTION

FIG. 1 is a front perspective view;

FIG. 2 is a rear perspective view;

FIG. 3 is a side elevational view; and,

FIG. 4 is an elevational view of the opposite side of that shown in FIG. 3.

The broken lines showing of wheels is for illustrative purposes only and forms no part of the claimed design.
